FASTENING FOR ATTACHE AND SUITCASES
AND THE LIKE

Charles William Cheney, Hockley, England

Application February 24, 1947, Serial No. 730,375

In Great Britain February 25, 1946

1 Claim. (Cl. 292—153)

1

The invention relates to fastenings for attaché and suitcases and the like, of the kind in which the bolt thereof is withdrawn by manual operation of a slideable knob arranged on the face of the front plate of the fastening and in which a relatively revoluble ring-member arranged concentrically of said knob is adapted to be hand-operated to block the withdrawal of the bolt by co-operation with a stop on the casing of the fastening.

The invention herein disclosed is an improvement over and simplification of applicant's own prior Patent No. 1,624,859, granted April 12, 1927.

Fastenings for attaché cases and the like are usually provided with key-locking mechanism which, when the fastenings are to be made safe, demand the insertion and operation of a key in a key hole formed in the slideable knob.

The public daily uses attaché cases for carrying personal belongings which in many instances may not properly be described as valuables but which, nevertheless, are important to the owner, and it is common practice not to use the key locking mechanism for ordinary or routine journeys either due to carelessness or failure to find the key. In this unlocked condition of the fastenings, should the spring loading the bolt fail, the fastenings will not longer be secure, while in the event of the knob being accidentally retracted, as often occurs when one mingles with a crowd, the same insecurity obtains and the case may unexpectedly open and the contents become upset and damaged or lost.

To guard against this disadvantage, the revoluble ring-member was employed, and in the past this revoluble ring-member has been mounted either between the face of the attachment plate and the back of the knob or rotatably mounted on a key peg of the fastening, the key for which is necessarily of the "pipe" type; this is undesirable because the bit of the key is usually so small that very little modification in its shape is possible. The knob and the ring were two parts handled separately when assembling the fastening.

One of the objects of the invention is to provide a fastening of the kind so that the hand blocking of the bolt against withdrawal and also the hand projection of the bolt into the fastening position is made clearly visible upon the face of the casing, and another object is a knob construction which is connected to the bolt only and not to any part of the casing and which is assembled and applied as a one-piece component of the fastening.

2

A fastening according to the invention, and which is hereinafter fully described and specifically claimed, comprises a casing with a fixed projection on its face, a bolt slideable in the casing and a hand-operable knob-unit consisting of a permanently assembled centre-member and ring-member, the latter being rotatable upon the centre-member and having a cam-piece to operate visibly against the fixed projection on the casing to block retraction of the bolt and to project the bolt into fastening position if, for any reason, the bolt spring fails.

It will be clear that the knob-unit connects only to the bolt and that the cam-piece of it is the only part using the projection on the casing for bolt blocking and projecting.

The invention will now be described with reference to the accompanying drawings wherein:

Fig. 1 is a plan of a fastening for an attaché case.

Fig. 2 is a diagrammatic longitudinal section of Fig. 1.

Fig. 3 is an underside plan of the slideable knob comprising the centre member and the relatively revoluble ring-member assembled as a unit.

Fig. 4 is a composite view showing the centre member and the ring-member in section prior to assembly.

In the drawing, 1 is the front plate of the fastening and 2 the back plate thereof, and between these plates 1, 2, there is a slideable spring-loaded bolt 3 whose nose is adapted to engage a hasp (not shown) through the hasp opening 4 in the front plate 1. This bolt 3 is adapted to be retracted by a manually operable slideable knob 5 on the face 6 of the front plate 1 and this knob 5 consists of at least two essential parts—a circular centre member 7 and a concentric ring-member 8, which latter is rotatably mounted on the centre member 7 and adapted to block retraction of the bolt 3 when partially rotated into a position when the ring-member co-operates with the casing 1. In the example shown, this ring-member 8 is cupped into hollow form from a sheet metal blank and includes a pair of diametrically opposite knobs 9, forming finger grips, and a cam-piece 12 extending from one of the knobs 9 to the normal boundary of the base

13 for approximately a quarter of the circumference of the ring-member 8. On the casing 1, adjoining the composite knob 5, is an integral projection 14 which when the ring-member 8 is rotated through approximately 90° co-operates 55 with the edge of the cam-piece 12 and operates

as an abutment thereby to resist retraction of the bolt 3. Alternatively, the cam-piece 12 could be dispensed with and a lug or stop on the interior of the ring-member 8 may be arranged to abut against the edge 15 of the usual opening 16 in the front plate 1. It is preferred, however, to employ the cam-piece 12 and projection 14 since by simply twisting the ring-member 8 into a position when the cam-piece abuts against the projection 14, the user can see at a glance that the bolt cannot be retracted by the knob 5 and therefore that the fastening is in a condition of security.

The centre member 7 is a sheet metal pressing having a key hole 16, a coned boundary flange 17, providing an inturned undercut formation, and two parallel ears 18 adapted to engage suitable openings in the bolt 3 and to be clinched thereon. The ring-member 8 has a conical flange 19 in its bore, which fits over the conical boundary flange 17 of the centre member 7, and two lugs 20 which are closed inwardly over the flange 17 thereby to closely and permanently connect the ring-member 8 to the centre member 7 and constitute a knob unit 5 so that the former can be partially revolved upon the latter for blocking retraction of the bolt 3 as hereinbefore explained.

The key hole 16 shown is of common shape for purposes of illustration, but any kind of key hole and key can be used for key-operated mechanism (not shown), i. e., a pipe or peg key or a flat key having a notched shank.

It is a great advantage from a mass assembly aspect to handle the centre member and ring-member as a knob unit ready for application to the bolt, and the way the ring-member is rotatably mounted on the centre member permits any kind of known key to be used for the key locking mechanism.

What I claim is:

A lock for attaché cases and the like comprising a casing having a front plate and a back plate, and a bolt slideable between the two, the front plate having a knob receiving slot and a hasp slot, said bolt being projectable past the hasp slot; a knob unit slideable on the face of the front plate, said unit including a skirt member having one end resting on said front plate, the other end being flanged inwardly and forming a conical wall; a central knob portion insertable into said skirt member and having an inturned conical wall resting on the conical wall of the skirt member, the wall of said skirt member having ears bent over the wall of the central knob portion to secure the parts rotatably together; the wall of the central knob portion having ears extending through said skirt and knob receiving slot and being rigidly connected to said bolt, said knob unit being slideable with said bolt; a stop member fixed on the face of said front plate at the end opposite said hasp slot and adjacent said skirt member, said skirt member having a cam along a portion of its periphery rotatable into position in front of said stop member to prevent retraction of said bolt.

CHARLES WILLIAM CHENEY.
